Filed Sept. 6, 1956, Ser. No. 608,401

5 Claims. (Cl. 101—134.5)

This invention relates to a transfer machine and more particularly to a machine for posting ledger sheets by the process of preparing a negative record on the back of the original record and through the use of a suitable solvent and pressure transferring the negative record to the face of the ledger sheet.

Such transfer machines in the past have accomplished the transfer of the negative record or carbon from the back of the original record by squeezing the solvent from a ribbon through the original record so that the subsequent pressure transfers the then wet carbon impression to the ledger sheet. The original is then moved forward to the next position as the ledger sheet and ribbon remain in a standby position. In accordance with the present invention an improved machine has been devised which utilizes a container of solvent fluid under pressure and a tubing for carrying the solvent, said tubing having a series of drilled jets so that the solvent may be released as a spray. Control means are provided to release the solvent spray just prior to the moving forward of the original sheet to the print position and the spray is applied directly to the carbon side of the original sheet. The use of such a spray system results in many advantages particularly from the standpoint of greater speed of operation and better printing quality.

Accordingly, the main object of the present invention is to provide a transfer machine having an improved moistening device for the record sheets employed in such machine.

A further object of the present invention is to provide a transfer machine having moistening means for applying solvent directly on the carbon side of the original sheet to obtain better printing quality.

A further object of the present invention is to provide a transfer machine provided with means for spraying the solvent on the carbon side of the original sheet before the original sheet is shifted into physical contact with the ledger sheet thereby greatly speeding up the posting operation.

A still further object of the present invention is to provide a transfer machine having a moistening device which permits the use of a non-toxic solvent which can be less severe in its action since it is not required to force the solvent through the paper to release particles of carbon.

A further object of the present invention is to provide an improved transfer machine wherein space is saved by the elimination of miscellaneous parts such as a solvent pan, ink ribbon, ribbon feed mechanism, and the like.

Other objects of the invention will be pointed out in the following description and claims and illustrated in the accompanying drawings, which disclose, by way of examples, the principle of the invention and the best mode, which has been contemplated, of applying that principle.

In the drawings:

FIG. 1 is a top plan view of the machine.

FIG. 2 is a detail view of the posting mechanism and the sheet feeding devices.

FIG. 3 is a section taken on lines 3—3 of FIG. 2 and showing the driving instrumentalities of the machine.

FIG. 4 is a detail view of the clutch and clutch release mechanism.

2

FIG. 5 is a detail of the operating mechanism for operating the ledger sheet clamps.

FIG. 6 is a detail of the operating mechanism for the ledger sheet carriage.

FIG. 7 is a detail of the line space mechanism.

FIG. 8 is a detail of the control valve for releasing the solvent to the spray tubing.

The original paper from which the copy is to be taken is printed in a conventional manner on a tabulator, typewriter or other suitable medium and is backed with suitable carbon paper while being printed. The original may take the form of single sheets, fanfold or continuous roll.

The machine in its general operation is substantially the same as that disclosed in Patent No. 2,282,737, granted May 12, 1942. The general operation will, therefore, be but briefly described with the improvements of the present invention more particularly explained.

The machine includes a table or plate 21 (FIG. 2) supported between side frames 22 and 23 (FIG. 3). Upon this table is placed the ledger sheet to receive the impression. The frames 22 and 23 are rigidly joined by a lower pressure bar 24, bar 25 and a motor support plate 27.

A motor 28 (FIG. 3) provided to drive the several mechanisms of the machine is mounted on the plate 27. The motor, through a pulley and belt connection 29 and a gear box 30 supported on the plate 27 operates a short shaft 31 supported in bracket 32 and secured to the plate 27. A clutch disk 34 (see also FIG. 4) fast on the shaft 31 is provided with notches 35 about its periphery, with which notches a clutch pawl 36 pivotally carried by a clutch arm 37 fast on a cam shaft 38 cooperates. The cam shaft 38 is supported in brackets 39 secured to the plate 27, the shaft 31 and 38 being in axial alignment.

The arm 37 (FIG. 4) and shaft 38 are normally held against rotation by an arm 40 fast on a stud 41 supported by the bracket 32. The arm 40 has a shoulder 42 which normally lies in the path of the arm 37 and of a tail of the pawl 36, thus holding the pawl 36 out of engagement with the disk 34. A stud 43 on the arm 40 fast on the stud 41 projects through a slot 45 in a link 46 whose right-hand end is supported by a spring 46a. The other end of the link is connected to an arm 47 fast on a shaft 48 journaled in the frames 22 and 23. Also fast on the shaft 48 is a release bar 49, located near the end of the shaft and being arranged to lie conveniently on one side of the table 21.

In order to initiate an operation of the machine, the operator depresses the bar 49, which movement rocks the shaft 48 and arm 47 counterclockwise thrusting the link 46 toward the right. At this movement, the left edge of notch 45 engaging the stud 43 rocks the arm therewith, removing the shoulder 42 from engagement with the arm 37 and the tail of the pawl 36. The pawl thus freed, is engaged with one of the notches 35 by a spring 56. The arm 37 and the shaft 38 make one complete counterclockwise rotation.

A cam 57 fast on the shaft 38 adjacent the extension 50 of link 56 has a single notch in its periphery cooperating with a roller 58 on the extension 50. As soon as the shaft 38 starts to rotate, the cam 57 rocks the extension 50 clockwise freeing the arm 40 to be acted upon by a spring 59 which immediately restores the arm to its normal position. Near the end of the rotation of shaft 38, the shoulder 42 reengages and rocks the pawl 36 out of engagement with the disk 34 and stops the arm 37 and shaft 38. A spring pressed retaining pawl 60 prevents retrograde movement or rebound of the arm 37.

If the operator has released the bar 49 before the end of the rotation of shaft 38, the parts assume their normal

positions when the notch in cam 57 comes opposite the roller 58. However, if the bar 49 is held depressed, holding the link 46 in its moved position, that is, toward the right, then when the cam 57 releases the roller 50, the pin 43 will rest on top of the link 46 and it will be necessary for the operator to release the bar 49, permitting a spring 61 having one end attached to an arm 62 fast on the shaft 48 to restore the link toward the left before another operation may be initiated.

Ledger carriage

The ledger sheet indicated at 63 (FIG. 2) on which the transfer is to be made is placed on the table 21, with the first line (in the case of a new sheet) or the next blank line on which a copy is to be made beneath a transparent line finder 64 adjustably mounted on a bar 55. This finder has parallel lines scribed thereon to assist the operator in the proper positioning of the ledger sheet. The sheet is located on the table 21 with its left edge beneath spring pressed clamps 65 (FIG. 5), there being four clamps 65 mounted on the ledger carriage.

The ledger carriage includes a bar 66 (FIG. 5) integral with a pair of spaced blocks 67 slidably mounted on rods 68 which are supported in brackets 69 (FIG. 3) secured to and extending inwardly from the left side frame 22. The clamps 65 are slideable vertically in the bar 66 and are normally urged downwardly to grip the paper 63 by blade springs 71 secured to the under side of the bar 66.

After the ledger sheet is in proper position, the operator depresses the release bar 49 whereupon the shaft 38 rotates. Shortly thereafter, a cam 72 (FIG. 5) permits a spring 73 to rock clockwise an arm 74 mounted on a shaft 75 supported in the brackets 39 (FIG. 3). An arm 76 fast to a shaft 77 (FIGS. 3 and 5) is connected by a link 78 to the arm 74. Also fast on the shaft 77 is a bell crank 79 whose downwardly extending arm is connected by a link 80 to a bell crank 81 pivoted on a stud projecting from a fixed bracket. A bar 82 supported on the bell cranks 79 and 81 is normally pressed upwardly against the paper clamps 65 and against the tension of springs 71 by the cam 72.

The clockwise movement of the arm 74 described above is transmitted by the link 78 to rock the arm 76, shaft 77, bell crank 79 and due to the connection 80 the bell crank 81 counterclockwise to lower the bar 82. This permits the springs 71 to draw the clamps 65 down gripping the ledger sheet firmly between said clamps and the carriage bar 66.

Shortly after the ledger sheet is gripped in the manner just described, mechanism now to be described is operated to shift the carriage a distance sufficient to move the selected line from its position beneath the line finder (FIG. 2) to a position under a pressure bar 83. This mechanism includes a pair of cams 84 (FIGS. 3 and 6) cooperating with a bell crank 85 pivoted on the shaft 75 and which is connected by a link 86 to an arm 87 fast to a shaft 88 supported between the side frames 22 and 23. Another arm 89 also fast on the shaft 88 carries at its free end a pin 92 extending between spring connected arms 91 which also cooperate with the pin 93 in an arm 90. The arm 90 is connected by a link 96 to the rear block 67 of the ledger carriage. The spring 97 between arms 91 serves as a safety coupling between arm 89 which is secured on shaft 88 and arm 90 which is free on the shaft, the rocking of arm 90 in either direction being through spring 97.

As the shaft 38 rotates, the bell crank 85 is rocked clockwise, which movement through the link 86 rocks the arm 87, shaft 88 and arm 89 in the same direction. This movement through the link 96 draws the carriage toward the right (FIGS. 2 and 6) and toward the rear of the machine for the purpose set forth above.

In order to align the typed matter on the original sheet with the proper column on the ledger sheet, there is provided a plurality of index fingers 51 (FIG. 2) each at-

tached to a gripping shield 51a slidably mounted on a rod 52 supported for oscillation between the frames 22 and 23. The ledger sheet 63 is placed in position on the table 21 and manually shifted to position beneath the pressure bar 83, at which point it is directly under the fingers 51. The fingers are now adjusted along the rod 52 to bring the fingers in line with the limits between which is it desired to have the transfer appear. With the fingers 51 in their selected positions, the original sheet 153 is inserted and the first line of typed matter is positioned with the top of the typed matter aligned with the bottoms of the fingers 51. The arms 164 (FIG. 2) are now operated to bring the rolls 139 into contact with the roll 137, thus holding the original sheet 153 in position.

Moistening device

As was previously mentioned, the moistening device employed by prior transfer machines, such as disclosed in the patent referred to, comprised a solvent reservoir and 20 a ribbon for applying the solvent to the non-carbon side of the original sheet. In accordance with the present invention this type of moistening device has been replaced with an improved arrangement which utilizes a container of solvent fluid under pressure and a tubing for carrying 25 the solvent. The tubing has a series of drilled jets so that the solvent may be released as a spray just prior to the moving forward of the original sheet to the print position and the spray is applied directly to the carbon side of the original sheet.

30 Referring to FIGS. 1 and 2, the container C of solvent fluid under pressure preferably is of the pressure "bomb" type of which there are many on the market which could be used. The container is mounted in any suitable fashion and has an outlet tubing T1 for transmitting the fluid 35 in the container into a control valve V. Leading out of the valve is another tubing T2 which extends downwardly and then laterally across the machine. The laterally extending portion of tubing T2 is provided with a series of small spray holes S (FIG. 1) and is located in a position which is approximately one line space in advance of the pressure bar 83 at the impression transfer position. As shown in FIG. 2, the laterally extending spray portion of tubing T2 closely underlies the master or original sheet 153 and the solvent is sprayed directly on the mirror image 45 appearing as a coated deposit on the back of the original sheet.

The transfer operation may be performed approximately three times faster with the present arrangement by reason of the fact that the solvent material is sprayed on the 50 master sheet before the master sheet is shifted into physical contact with the copy paper and this improvement in time permits the use of a non-toxic solvent which, for example, may consist of only alcohol and Freon gas and which can be less severe in its action since it is not required to force the solvent through the paper to release 55 particles of carbon or ink.

The valve V controls the release of the solvent and may take any suitable form. For example, as shown in FIG. 60 8, a valve may be provided which comprises a spring tensioned slidable plunger P which normally obstructs the flow of solvent between a port A associated with tubing T1 and a port B associated with the tubing T2. The plunger includes a through hole H and may be moved upward to position the hole in alignment with the parts and thus release the solvent for a spraying operation.

For cyclically operating the valve plunger there is provided a sector 122 (FIG. 2) free on a shaft 114 and having a camming lobe L which coacts with a flange F on the end of the plunger. A cam 115 on the shaft 38 70 rocks an arm 116 on the shaft 75 counterclockwise against the tension of a spring 133 and by a connection 117 rocks a lever 118 clockwise. The lever 118 is secured on a shaft 112 whose one end has an arm 118a fast thereon. The upper end of arm 118a cooperates with a stud 75 121 on the sector 122 rocking the sector counterclock-

wise against the tension of a spring 132 causing the camming lobe L to engage the plunger and open the valve to release the solvent spray.

Pressure bar

The pressure bar 83 is slideable vertically in grooves 125 in the side frames 22 and 23 (FIGS. 1 and 2) and is operated by a pair of links 126, one being pivotally connected to the bar 83 near each end. The links 126 are connected at their lower ends to arms 127 fast on a shaft 128 (FIG. 3), one of said arms being disposed near each end of said shaft. An arm 127a (FIG. 3) is connected by a link 129 to one arm of a bell crank 130 pivoted on the shaft 75. A pair of cams 136 on the shaft 38 cooperates with antifriction rollers on the bell crank 130 to rock it first clockwise and then counterclockwise to normal. The clockwise movement of the follower through the link 129, arms 127 and links 126 lowers the pressure bar 83 to cause the transfer and the counterclockwise movement of said bell crank 130, through the same linkage, raises the pressure bar to normal position.

Paper feed—original

Referring to FIG. 2, a feed roll 137 is mounted on a shaft 138 journaled in the frames 22 and 23. A plurality of pressure rolls 139 each carried between a pair of arms 140 are pressed against the roll 137 by springs 141. The arms 140 are pivotally mounted on a shaft 142 supported in brackets secured to the cross bar 25.

Secured to one end of the shaft 138 is a ratchet wheel 144 (FIG. 7) with which cooperates a spring pressed feed pawl 145 carried on an arm 146 free on the shaft 138. A link 147 connects the arm 146 to an arm 148 pivotally supported on the frame 22. An antifriction roller 149 normally rests on the flattened end of an arm 150 secured to the shaft 88.

It will be remembered that the shaft 88 rocks first clockwise and then back to normal position under the influence of the cams 84, the arm 150 making a similar excursion (FIG. 3). When the arm 150 rocks clockwise from beneath the roller 149, a spring 151 draws the arm 148 and link 147 downwardly rocking the arm 146 clockwise to retract the pawl 145. After a transfer has been made, the cams 84 cause the arm 150 to rock counterclockwise to normal position, at which movement an inclined or cam surface 150a of the arm 150 moves the link 147 upwardly rocking the arm 146 counterclockwise to feed the original copy one line space. A spring pressed retainer 152 serves to hold the roll 137 and the original copy in alignment.

The original from which a transfer is to be made, indicated at 153 in FIG. 2, is inserted over a shield 154 passing between a bar 155 and a plate 156, between the feed roll 137 and the rolls 139 and over the arms 140. The bar 155 is carried between two arms 159 pivoted on a shaft 160 supported in the brackets 143. The plate 156 is secured to the shaft 160 and is normally held in the position in which it is shown in FIG. 2 by springs 162 attached to levers 163 which are also secured on the shaft 160.

In order to insert an original copy sheet, a pair of arms 164 (FIG. 2) is rocked counterclockwise. These arms are secured one on each end of a shaft 165 journaled in the brackets 143, and which shaft is provided with notches into which fit the arms 140. Upon counterclockwise movement of the arms 164 and shaft 165 the flattened portions of the shaft bearing against the arms 140 rock these arms also counterclockwise to separate the rollers 139 from the feed roll 137. During this movement studs 166, one on each of the arms 140, contact the plate 156 and carry the latter therewith, the parts being shown in their moved positions in dotted outline in FIG. 2. This provides a free passage for the original sheet 153 between the bar 155 and plate 156 and between the feed roll 137 and the pressure rolls 139.

When the arms 164 are restored clockwise to their normal position, the springs 141 press the original sheet 153 tightly between the rolls 139 and the feed roll 137. The clockwise movement of the bar 155 is limited by the arms 159 striking collars on the shaft 138 and with the parts in their normal position, as shown in FIG. 2, there is a slight clearance between the bar 155 and plate 156 to permit free movement of the original 153 when line spaced as above described.

At the completion of a transfer operation and as soon as the pressure bar 83 starts moving upward to release the pressure, the mechanism illustrated in FIG. 6 moves the ledger carriage to its original position and the cam 72 (FIG. 5) raises the bar 82 to release the grippers 65. The operator may now adjust the ledger sheet 63 to the next line or insert another sheet to the next unused line. Also near the end of the restoration of the pressure bar, the paper feed mechanism (FIG. 7) operates to feed the original sheet 153 one line space and cam 115 is timed to effect the release of the spray solvent just prior to this movement.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a machine of the class described having an original sheet to be transferred, a table to support a copy sheet, a pressure bar to press the original sheet and copy sheet together, said bar being repeatedly operable, in combination with means for engaging said original sheet to line space the same for each operation of the pressure bar, a source of solvent fluid, means operable to direct a spray of said fluid on said original sheet no more than one line space in advance of the pressure bar, and means for operating said last-named means just prior to each line spacing operation while said original sheet is at rest.
2. In a machine of the class described comprising an original sheet having a dye side to be transferred, a table to support a copy sheet in alignment with and adjacent to the dye side of said original sheet, a pressure bar to press the original sheet and copy sheet together, said bar being repeatedly operable, in combination with means for engaging said original sheet to line space the same for each operation of the pressure bar, a source of solvent fluid, means operable to direct a spray of said fluid against the dye side of said original sheet one line space in advance of the pressure bar, and means for operating said last-named means just prior to each line spacing operation while said original sheet is at rest.
3. In a machine of the class described comprising an original sheet having a dye side to be transferred, a table to support a copy sheet in alignment with and adjacent to the dye side of said original sheet, a pressure bar to press the original sheet and copy sheet together, said bar being repeatedly operable, in combination with means for engaging said original sheet to line space the same for each operation of the pressure bar, a source of solvent fluid under pressure, release means connected to said source and normally preventing the release of said fluid, means connected to said release means for transmitting released solvent fluid and including a series of jets extending laterally across said machine and positioned one line space in advance of said pressure bar for directing the fluid in the form of a spray against the dye side of said original sheet, and cyclically operable means for operating said release means while said original sheet is at rest to release said fluid for a transferring operation.
4. In a machine of the class described comprising an

original sheet having a dye side to be transferred, a table to support a copy sheet in alignment with and adjacent to the dye side of said original sheet, a pressure bar to press the original sheet and copy sheet together, said bar being repeatedly operable, in combination with means for engaging said original sheet to line space the same for each operation of the pressure bar, a container of liquid alcohol and Freon gas under pressure, means operable to release a spray of said liquid against the dye side of said original sheet, and means for operating said release means just prior to each line spacing operation for a relatively long wetting period during which said original sheet is at rest.

5. In a machine of the class described comprising an original sheet having a dye side to be transferred, a table to support a copy sheet in alignment with and adjacent to the dye side of said original sheet, a pressure bar to press the original sheet and copy sheet together, said bar being repeatedly operable, in combination with means for engaging said original sheet to line space the same for each operation of the pressure bar, a source of solvent fluid, means operable to direct a spray of said fluid

10

15

20

against the dye side of said original sheet when at rest for a relatively long wetting period, means effective at the termination of said wetting period for operating said line spacing means to quickly line space said original sheet, and means effective at the end of said line spacing operation to operate said pressure bar to quickly effect a print transfer.
